DISH MOP

Toussaint Beunkes, Arnhem, Netherlands, assignor to Algemeene Kunststijle Unie, N.V., Arnhem, Netherlands, a corporation of the Netherlands

Filed May 10, 1962, Ser. No. 193,736

Claims priority, application Netherlands May 12, 1961
3 Claims. (Cl. 15—244)

This invention relates to mops of the type which have one or more rosette-shaped bodies of spongy material fastened at the end of a handle and to the cutting of such rosette-shaped bodies from a large sheet of sponge-like material under waste-free conditions.

It is known in the art to make dish mops out of sponge-like elastic material such as sponge rubber and regenerated cellulose. These materials are cut in various shapes and are fastened to the end of a handle. In general it is desirable to have the spongy bodies present a somewhat irregular surface so that mechanical scrubbing action can be achieved.

One of the most desirable shapes to use for the manufacture of mops of this type, particularly for washing dishes, is a rosette cut from a sheet of suitable spongy plastic material. Heretofore, these rosettes have been cut so that the resulting profile provides a number of projecting arcuate scrubbing surfaces. While mops made from these do a good scrubbing job, a disadvantage of such rosettes is that in cutting them from a sheet of the plastic sponge there is a very considerable amount of waste.

It is therefore an object of this invention to provide a rosette of novel shape which will retain the scrubbing advantages of the prior art but which may be cut from a sheet of sponge material with negligible waste.

Other objects and advantages of this invention will be apparent upon consideration of the following detailed description of a preferred embodiment thereof in conjunction with the annexed drawings wherein:

FIGURE 1 is a view of a dish mop constructed in accordance with the principles of the present invention with the sponge head in cross-section;

FIGURE 2 is a top plan view of a group of four rosettes cut in accordance with the teachings of the present invention showing how they interfit to minimize waste;

FIGURE 3 is a schematic view showing the method of calculating the rosettes of the present invention for minimizing waste; and

FIGURE 4 is a sectional view taken along line 4—4 of FIGURE 1 in the direction of the arrows.

Referring now to FIGURE 1, the mop there shown consists of three rosettes 1, 2 and 4, suitably supported in a mutually offset manner on the end of a handle 17. These rosettes may be cut from a small sheet of spongy material and when this is done cutting dies are so arranged that each rosette, while of the same shape as every other rosette, is disposed on the sheet at an angular position 90° away from the adjacent rosettes. Each rosette includes four rounded corners 5, 7, 8 and 10, two outwardly curving sides 6 and 9, and two inwardly curving sides 11 and 12, and a center hole to receive a stud or the like which connects them to a handle. As can be seen in FIGURE 2, the contours of adjacent rosettes are rotated relative to each other a quarter of a turn so that always one of the outwardly projecting sides or protuberances fits in an inwardly curving side of an adjacent rosette. It is this arrangement on the sheet that gives rise to the saving of material.

In FIGURE 3 the numeral 13 refers to the square which is the basic shape from which the rosette is cut. Let us assume for a dish mop that the sides of this square are 6

2

centimeters. The corners 5, 7, 8 and 10 are rounded off in the form of semicircles.

Between the arcs of circles 5 and 7 and the arcs of circles 8 and 10 there fit the semi-circles 6 and 9 respectively, which semi-circles represent the circumferences of the outwardly curving sides.

The arcs of circles 5 to 10 inclusive have an equal radius 15, their centres lying on a common circle having a radius 14.

10 The radius 14 is

$$\frac{2+3\sqrt{2}}{14}$$

times the side of the square 13.

15 The radius 15 is

$$\frac{4-\sqrt{2}}{14}$$

20 times the side of the square 13.

The arcs of circles 5 and 8, and the arcs of circles 7 and 10 are curvilinearly connected respectively by arcs of circles 11 and 12, the radius 16 of which is equal to 2 times the radius 15.

25 The outwardly curving sides 6 and 9 project beyond the square 13 practically to the same extent as the inwardly curving sides 11 and 12 extend beyond the sides of the square in opposite direction.

It appears that with a proper arrangement of the contours the minimum slit width which remains between the mating outwardly and inwardly curving sides need amount to less than 1% of the length of a side of the square. With the above-described shape of the rosettes the amount of starting material wasted is negligible.

35 Although the rounded corners and the outwardly and inwardly curving sides may be separated from one another by parts of the sides of the square, it is found that a fuller rosette shape is obtained if the rounded corners and the outwardly and inwardly curving sides are next to one another.

40 To obtain a well shaped rosette, the symmetry of which moreover permits the rosette-shaped plates to be manufactured in a simple manner, the rounded corners and the outwardly curving sides are, according to the invention, in the form of semi-circles, the centres of which lie on the same circle.

45 The inwardly curving sides must recede such that an outwardly curving side of another rosette fits perfectly therein.

50 On the other hand, the inwardly curving side must not be deeper than is necessary, in order to prevent unnecessary weakening of the rosette-shaped plates.

FIGURE 4, a sectional view taken along line 4—4 of FIGURE 1, illustrates how the rosettes are assembled in a stack on the handle 17 in an offset manner with protuberance of one rosette directly overlying the inward curve of an adjacent rosette in order to present a maximum number of scrubbing surfaces along the circumference of the mop. In actual practice three or more rosettes, as shown in FIGURE 1, would usually be assembled on a single handle in this manner.

60 What is claimed is:

65 1. A dish mop which comprises at one end of a handle a plurality of rosettes of a porous, resilient, sponge material, the basic shape of the rosette being substantially a square with rounded corners, two opposite sides each having a single outwardly curved protuberance projecting beyond said basic square and the other two sides each having an inwardly curved portion, the area bounded by each of said inward curves and a portion of said basic square being greater than the area of each protu-

berance, said plurality of rosettes being secured to said handle in an offset manner to form a stack with the protuberances of one rosette being opposite the inwardly curved portion of an adjacent rosette.

2. A dish mop according to claim 1, characterized in that the rounded corners and the outwardly curved protuberances are shaped as semi-circles, the centers of which are spaced in arc on different radii of the same circle.

3. A dish mop according to claim 1, characterized in that the inwardly curved portions are shaped as arcs of

circles, each of which curvedly inter-connects two rounded corners of the square.
